Primary Examiner — Philip S Hyder*Assistant Examiner* — Roselynne Cody(74) *Attorney, Agent, or Firm* — Ridout & Maybee LLP; Mark A. Koch(57) **CLAIM**

The ornamental design for a flat nozzle, as shown and described.

DESCRIPTION

FIG. 1 is a front elevational view of a flat nozzle.

FIG. 2 is a side elevational view thereof.

FIG. 3 is a top plan view thereof.

FIG. 4 is a bottom plan view thereof; and,

FIG. 5 is a top perspective view thereof.

The broken lines in the figures illustrate portions of the flat nozzle that form no part of the claim.

1 Claim, 3 Drawing Sheets(56)
